Primary Examiner—Sandra L. Morris
Attorney, Agent, or Firm—Gardner, Carton & Douglas[57] **CLAIM**

The ornamental design for a dart game target, as shown and described.

DESCRIPTION

FIG. 1 is a front view of the dart game target, showing my new design, the broken line showing of the numerals is for illustrative purposes only, and forms no part of the claimed design;

FIG. 2 is a right side view of the dart game target; The left side view of the dart game target corresponds to FIG. 2; and,

FIG. 3 is a top view of the dart game target. The bottom view of the dart game target corresponds to FIG. 3.

The appearance of the back of the dart game target forms no part of the design invention.
